DEHYDRATOR PLUG

Harry A. Lockwood, Westport, Conn., assignor to
 Clark Metal Products, Inc., Fairfield, Conn., a
 corporation of Connecticut

Application April 22, 1947, Serial No. 743,184

9 Claims. (Cl. 183—4.8)

1

The present invention relates to a dehydrator plug for the purpose of attachment to a closed structure for removing moisture from the interior of such structure, and in certain types of structure for preventing corrosion therein due to humidity. A particular application of the invention is to internal combustion engines while in storage or shipment, the plugs adapted to be screwed into the spark plug openings after removal of the spark plugs, so that the interior of the engine is exposed to a desiccant contained in the plug, such desiccant being, for example, silica gel crystals.

Dehydrator plugs have been employed for this purpose heretofore, but their construction and operation have been such as to result in certain disadvantages, which it is an object of the present invention to overcome. For instance, certain plugs have been constructed of thermo-plastic material, which had a relatively high water vapor transmission rate through the walls surrounding the desiccant, with the result that the desiccant was not effectively sealed from ambient atmosphere while the plug was in use or in storage. In either case rapid deterioration of the desiccant would take place. Also such plugs have employed screens or slots for permitting access of the air in the engine cylinder to the desiccant and these were apt to permit small particles of the desiccant to drop into the engine cylinder. Also, the screen means employed was inserted from the lower end of the plug, so that in the event of failure of the screen retaining means, it was possible for the screen to drop into the engine cylinder, in which case it became necessary to disassemble the engine for the purpose of removing the screen and desiccant from the cylinder. A further disadvantage has been that the construction usually required that the desiccant be sealed in by the manufacturer, so that it could not readily be removed and renewed in the field.

It is an object of the present invention to provide a dehydrator plug in which the container for the desiccant is formed of material having an especially low water vapor transmission rate through its walls, such material being preferably glass. It is further proposed to provide such container, so located that the desiccant will be clearly visible through its walls when installed in the engine, when viewed either from the side or from the end. Another object is to provide sealing means which will effectively seal the desiccant prior to installation in the engine so that the necessity for storing in sealed metal containers, or the like, is eliminated.

Another object is to provide a desiccant retention means in the form of a filter through which

2

it is impossible for the crystals of the desiccant to drop, such filter being, for instance, a disc of compressed sintered material such as metal, glass, ceramics, or the like, which provides free passage of water vapor to the desiccant, and at the same time positively prevents the escape of dust or particles of the desiccant due to corrosion. It is further proposed to provide a plug structure in which the filter and other component parts are assembled in the plug from the upper end and are positively retained against any possibility of falling into the engine cylinder.

Another object is to provide a dehydrator plug which permits the easy replacement of expended desiccant, and it is particularly proposed to provide means which can be operated with the fingers alone, without the necessity for tools, for the purpose of removing and replacing the desiccant. A further object is to provide a dehydrator plug in which the glass container is effectually protected against breakage, either due to physical contact therewith, or due to shock, the latter object being accomplished by means of a floating or cushioned mount for the glass container.

Another object is to provide a dehydrator plug which is so constructed that at strategic points dissimilar metals which would produce electrolysis are not in contact, this condition being carried out both in the plug itself when not in use, and in the installation of the plug in the engine.

A further object is to provide a plug having a high resistance to cold flow, so that loosening of the threads due to temperature induced contraction is prevented. In particular, it is proposed to construct the body portion of the plug from phenolic thermo-setting material, which has a high resistance to cold flow, as distinguished, for instance, from thermo-plastic material.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a side elevation of a dehydrator plug, according to the illustrated exemplary embodiment of the invention, the same being shown provided with a sealing cap prior to installation in the engine.

Fig. 2 is a top plan view thereof.

Fig. 3 is a horizontal sectional view, taken along the line 3—3 of Fig. 1, the desiccant material being removed.

Fig. 4 is a vertical sectional view, taken along the line 4—4 of Fig. 1.

Fig. 5 is a side elevation showing the installation of the plug in the engine cylinder.

Similar reference characters indicate corresponding parts throughout the several figures of the drawings.

Referring to the drawings, the dehydrator plug, according to the illustrated exemplary embodiment of the invention, comprises a cup-shape body member 10, preferably moulded from phenolic thermo-setting plastic material, having an annular external seating flange 11, and a downwardly extending threaded plug portion 12 for screwing into the spark plug opening 13 of the engine cylinder head 14, as shown in Fig. 5. Internally the body member is provided with a cylindrical pocket 15 for receiving the desiccant container, the base of this pocket being formed by an annular shoulder 16, and a counter-sunk annular recess 17, and a central passage 18 extending downwardly through the plug portion 12 from the recess 17.

Exteriorly the body member is provided with flats 19, giving it a hexagonal form, for the purpose of facilitating its engagement and disengagement with the engine, by means of a spark plug wrench, or the like. At diametrically opposed points there are provided flats 20 having upwardly inclined holes 21 formed therein for the purpose of receiving the ends of the spring clip member, as will hereinafter more fully appear.

Within the recess 17, there is seated a circular filter disc 22, preferably formed of sintered metal, glass, ceramics, or the like, and upon the shoulder 16 there is supported a rubber gasket 23, its outer periphery being in contact with the cylindrical wall of the pocket 15 and its inner periphery being inwardly spaced from the outer periphery of the filter disc 22. The filter disc 22 is slightly thicker than the depth of the recess 17, so that its slightly raised edge is effectually sealed by the rubber gasket 23. The desiccant container 24 is in the form of a cylindrical glass cup member, open at its lower end and closed at its upper end, its external diameter being such that it fits slidably within the cylindrical pocket 15, its lower edge seating upon the rubber gasket 23 in the assembled position.

Upon the upper closed end of the container 24 there is engaged a flanged cap 25, provided centrally with an upwardly extending tubular wall portion 26, preferably provided at its upper edge with a curled rim 27. The tubular wall portion 26 is provided at diametrically opposed points with vertically disposed slots 28, which are engaged by the upper transverse end of a bale-like spring clip member 29. This upper transverse end is provided with horizontal end portions and an upwardly bowed intermediate portion 30, the latter extending through the slots 28 while the horizontal end portions engage firmly with the upper surface of the cap at each side of the wall portion 26. The side legs extend downwardly in parallel relation at each side of the exposed portion of the glass container 24, their lower portions being outwardly offset by means of angular bends 31, so that these portions are disposed in parallel relation at each side of the body member 10, the lower ends of the side legs being provided with inwardly and upwardly inclined hooks 32 engaged in the upwardly inclined holes 21 provided in the body member. Each of the side legs is provided near the upper end of the clip member with a serpentine shaped spring section 33.

which permits yielding movement between the upper transverse end and the hooks 32.

In the assembled relation the upper transverse portion of the spring clip is under tension so that the cap 25 and the container 24 are firmly pressed downwardly, causing the lower edge of the container to press firmly into sealed relation with the rubber gasket 23, this downward pressure also firmly pressing the rubber gasket upon the shoulder 16 so that the container is effectually sealed. The sealing engagement of the gasket with the slightly raised edge of the filter disc 22 prevents dust particles from entering the engine cylinder. The condition of the desiccant can be readily seen either from the side through the wall of the container 24 or from the end through the tubular wall portion 26 of the cap. The side legs of the spring clip protect the sides of the glass container, and the cooperative effect of the spring clip and the rubber washer is to provide a floating mount for the glass container so that it is protected against breakage from shock. In filling the glass container 24 with the desiccant 34, the open end is held upwardly and the desiccant poured therein, the body member 10 being thereupon engaged downwardly upon the open end of the container. The body member and container may then be turned into upright position and secured by swinging the cap member and spring clip into retaining position. The yieldable spring clip may be swung into open and closed positions while the hook ends 32 remain in the holes 21, the bowed upper portion 30 permitting the upper end of the clip to clear the upper edge of the container as the cap is forced into or out of place thereon.

A flanged screw cap 35 is adapted to be screwed upon the screw plug portion 12 of the body member to seal it prior to installation in the engine, a rubber sealing gasket 36 being disposed between the flange 11 and the flange of the cap. As shown in Fig. 5, this gasket 36 may also be used upon installation of the plug in the engine cylinder to form a seal between the engine head and the flange 11.

I have illustrated and described a preferred and satisfactory embodiment of the invention, but it will be understood that changes may be made therein, within the spirit and scope thereof, as defined in the appended claims.

What is claimed is:

1. In a dehydrator plug, a body member of generally tubular form having an axial opening extending therethrough, said opening having an annular shoulder intermediate its ends forming a pocket at one side of said shoulder and an inlet passage for air at the other side, a desiccant container of inverted cup-shape having its open end engaged in said pocket above said shoulder, and a moisture permeable member extending entirely across and supported transversely in said opening and constituting a bottom support for the desiccant in said container.
2. In a dehydrator plug, a body member of generally tubular form having an axial opening extending therethrough, said opening having an annular shoulder intermediate its ends forming a pocket at one side of said shoulder and an inlet passage for air at the other side, a desiccant container of inverted cup-shape having its open end engaged in said pocket above said shoulder, and a moisture permeable member extending entirely across and supported transversely in said opening and constituting a bottom support for the desiccant in said container, and resiliently

yieldable retaining means connected between the closed end of said container and said body member to retain said container in said pocket.

3. In a dehydrator plug, a body member of generally tubular form having an axial opening extending therethrough, said opening having an annular shoulder intermediate its ends forming a pocket at one side of said shoulder and an inlet passage for air at the other side, a desiccant container of inverted cup shape having its open end engaged in said pocket above said shoulder, and a moisture permeable member extending entirely across and supported transversely in said opening and constituting a bottom support for the desiccant in said container, a cap member engaged with the closed end of said container, and resiliently yieldable retaining means connected between said cap member and said body member to retain said container in said pocket.

4. In a dehydrator plug, a body member of generally tubular form having an axial opening extending therethrough, said opening having an annular shoulder intermediate its ends forming a pocket at one side of said shoulder and an inlet passage for air at the other side, a sealing gasket seated upon said shoulder, a desiccant container of inverted cup-shape having its open end engaged in said pocket above said shoulder, with its edge in sealing engagement with said gasket, a moisture permeable member extending entirely across and supported transversely in said opening and constituting a bottom support for the desiccant in said container, and resiliently yieldable retaining means connected between the closed end of said container and said body member to retain said container in said pocket.

5. In a dehydrator plug, a body member of generally tubular form having an axial opening extending therethrough, said opening having an annular shoulder intermediate its ends forming a pocket at one side of said shoulder and an inlet passage for air at the other side, said shoulder having a counter-sunk recess, a desiccant container of inverted cup-shape having its open end engaged in said pocket above said shoulder, and a moisture permeable member engaged in said recess extending entirely across said opening and constituting a bottom support for desiccant in said container.

6. In a dehydrator plug, a body member of generally tubular form having an axial opening extending therethrough, said opening having an annular shoulder intermediate its ends forming a pocket at one side of said shoulder and an inlet passage for air at the other side, a desiccant container of inverted cup-shape having its open end engaged in said pocket, a moisture permeable member extending entirely across and supported transversely in said opening and constituting a

bottom support for desiccant in said container, a cap member engaged with the closed end of said container having a sight opening, and resiliently yieldable retaining means connected between said cap member and said body member to retain said container in said pocket.

7. In a dehydrator plug, a body member of generally tubular form having an axial opening extending therethrough, said opening having an annular shoulder intermediate its ends forming a pocket at one side of said shoulder and an inlet passage for air at the other side, a desiccant container of inverted cup-shape having its open end engaged in said pocket, a moisture permeable member extending entirely across and supported transversely in said opening and constituting a bottom support for desiccant in said container and a yieldable spring member having a transverse portion engaged with the closed end of said container and side leg portions pivotally connected to said body member to retain said container in said pocket.

8. In a dehydrator plug, a body member having an opening extending therethrough, said opening having a shoulder intermediate its ends forming a pocket at one side of said shoulder and an inlet passage at the other side, a moisture permeable member supported transversely in said opening, a desiccant container of inverted cup-shape having its open end engaged in said pocket, said body member having an external flange and an external threaded portion at one side of said flange, a threaded sealing cap engaged with said threaded portion, and a sealing gasket disposed between said flange and said sealing cap.

9. In a dehydrator device, a body member of generally tubular form having an axial opening extending therethrough, said opening having an annular abutment spaced below its upper end, desiccant retaining means engaged with said body member above said shoulder, and a moisture permeable member supported by said abutment and extending entirely across said opening to constitute a bottom support for the desiccant.
